CARTON OPENING KNIFE

Edward N. Burnett, San Lorenzo, Calif., assignor
to Gerber Products Company, Fremont, Mich.,
a corporation of Michigan

Application March 7, 1950, Serial No. 148,093

4 Claims. (Cl. 30—2)

1

This invention relates to a new and useful improvements in carton opening knife, and more particularly to a knife having a dual purpose, namely to separate two cartons temporarily joined together by a fibre extension, and to slit the side wall of a carton preparatory to removing the top thereof.

It will be understood that the instant invention comprises an inexpensive, compact, and safe utensil which may be used by retail merchants, warehousemen, or the like to cut the material of ordinary fibre boxes such as corrugated containers used to pack canned and bottled merchandise. The knife blade is moveable to two positions for use to accomplish either of the purposes heretofore named and the knife has a further safety position wherein all sharp edges are protected so that the knife may be handled or carried in the pocket or about the person of the user with safety.

Further objects of the present invention will become apparent upon reading the following specification and referring to the accompanying drawings in which similar characters of reference represent corresponding parts in each of the several views.

In the drawings:

Fig. 1 is a perspective of the knife as viewed in one direction with the blade in position for severing one carton from another.

Fig. 2 is a perspective similar to Fig. 1 but viewed from a different position.

Fig. 3 is a top plan of the knife with the blade in position for removing the top of a carton.

Fig. 4 is a side elevation of the structure shown in Fig. 3.

Fig. 5 is an end elevation of the structure shown in Fig. 3.

Fig. 6 is a schematic perspective showing the knife used to sever two cartons.

Fig. 7 is a perspective showing the knife used to remove the top of a carton.

Fig. 8 is a side elevation of the guard in retracted position.

As has been stated, the instant invention constitutes a dual purpose knife. One of its purposes is to sever two box units joined together by a fibre extension of one box glued to the adjacent box. Such boxes are illustrated and described in the co-pending application of Edward N. Burnett, Serial No. 141,150, filed January 28, 1950, and further illustrated in Fig. 6 hereof. It will be understood that reference numerals A and B indicate two complete box units joined together by means of integral tongues 11 and 12 projecting

2

outwardly from units A and B respectively and glued to upper surfaces of the adjacent box units. It will be understood that there are corresponding tongues projecting from the bottom surfaces of the units. It will be further understood that in lieu of the integral tongues joining the adjacent units together, non-integral pads of cardboard or corrugated material may be glued to the surface of two units to join them together. One use of the knife which constitutes the instant invention is to sever the connecting cardboard or corrugated paper bridging the two units without damaging the cartons or contents thereof so that, after severing, either or both units may independently be stored or shipped.

The other function of the knife is to remove the top of a box or box unit by cutting into the adjoining sides without damaging the contents packed therein. These and other functions of the knife will become apparent on consideration of the description of the structure thereof which follows:

The handle 16 of the knife is preferably formed in the shape of a U-shaped channel, the opposed surfaces of the respective legs 17 and 18 of the channel being spaced apart a distance only slightly greater than the thickness of the knife blade 19. Said blade 19 is provided with a hole adjacent one end thereof through which fits a screw 21, said screw also passing through parallel elongated slots 22 longitudinally disposed centrally with respect to each of the legs 17 and 18. Nut 23 threaded on screw 21 when tightened holds blade 19 in position longitudinally of the handle 16. Said screw 21 constitutes a pivot for the blade 19 so that the blade may be manually moved from the first position illustrated in Fig. 1 to the second position illustrated in Fig. 3, it being understood that the first position is intended for use in severing one carton from another (see Fig. 6) and the second position is used to remove the top from a carton (see Fig. 7).

The blade 19 in the portion opposite the end through which screw 21 passes is provided with two cutting areas in the vicinity of which the blade is sharpened, one area being useful when the knife is in first position and the other being useful when in second position. The first position area comprises a notch 26 cut into the top longitudinal edge of the blade so that the anterior portion of the blade resembles a hook 27 adapted to fit under tongue 11 or 12 and between the adjacent sides of box units A and B when said units are being severed. Notch 26 is shaped

with the edge 28 adjacent hook 27 cut back toward the tip of the blade at an angle of about 60° with respect to the longitudinal edge of the blade. Said edge 28 intersects the bottom edge 29 of the notch which is disposed parallel to the longitudinal edge of the blade and is positioned substantially midway between the top and bottom longitudinal edges of the blade. The third edge 31 of notch 26 is parallel to edge 28 and connects the top longitudinal edge of the blade 10 and bottom edge 29. It will be seen with reference to Fig. 6 that after the hook 27 has been inserted between units A and B and under tongue 11 or 12, as the operator draws the knife toward him the edges 28 and 29 of the notch 26 sever 15 the cardboard or corrugated paper which constitute tongues 11 and 12 for separation of the units A and B from each other. The point of hook 27 assists in locating the knife in proper position between the adjacent sides of the box 20 units A and B so that only tongues 11 and 12 are cut and the other portions of box units are not damaged.

The blade 19 may be swung from the position shown in Fig. 1 to the position shown in Figs. 3 and 4 about pivot 21. In such position, the tip of blade 19 extends beyond the end of handle 16. The tip of blade 19 is cut back as indicated by reference numeral 36 and the edge of the blade is sharpened in this zone.

Guide 37 is attached to the handle 16 by means of a plurality of studs 38 fixed to channel 18 and projecting through slot 39 in said guide 37. The heads of said studs are peened over so that the guide 37 may be moved longitudinally with respect to handle 16.

Guide 37 is formed with two parallel arms 41 and 42 respectively joined by perpendicular connecting off-set portion 43. Slot 39 is formed in arm 41 which is adjacent and parallel to channel leg 18 and slidably held by studs 38. Guide 37 is moveable to three positions, determined by the length of slot 39. In extended position off-set portion 43 covers the point of blade 19 so as to prevent the sharpened edge 36 thereof from being exposed. Thus the guide 37 constitutes a safety device preventing the user from being injured while the knife is handled or carried on the person. This position is illustrated in dot and dash lines in Fig. 3. A dimple 40 is struck up from the surface of leg 18 adjacent the end thereof, said dimple bearing against the undersurface of arm 41 and frictionally retarding movements of guide 37 so that positive manual movement is required to alter its position.

In the partially retracted position of the guide 37, shown in Fig. 4, off-set portion 43 extends the same distance as the end of the handle 16. The point of blade 19 and particularly the sharpened portion 36 extends beyond the off-set portion 43 and hence the cutting portion 36 is exposed for use. The amount said blade 19 extends may be adjusted by loosening nut 23 and sliding screw 21 in slot 22 thereof, thus moving blade 19 with respect to the handle 16. As blade 19 is moved toward the right as viewed in Fig. 1, the amount the blade will project beyond the portion 43 is decreased, whereas, as blade 19 is moved toward the left as viewed in Fig. 1, the amount which the tip of blade 19 projects is increased. This adjustment of the blade adapts the knife for use in cutting cartons of different thicknesses, it being intended that the amount which the blade projects will be adjusted so as to coincide with the thickness of the material being cut. With

the blade extended the proper distance, the underside of arm 42 is placed in contact with the top of the box and the off-set portion 43 is placed in contact with the side being severed. 5 The knife is then drawn along the side of the box and the cutting edge 36 of the blade 19 cuts through the side of the box.

A third position of adjustment results when guide 37 is fully retracted as shown in Fig. 8. The blade edge 36 is fully exposed and the guide is in operation in this position. The blade may thus be used to slit the container at any position.

Thus it will be seen that in the first position of adjustment of blade 19 hook 27 may be inserted between two box units so that cutting edges 28 and 29 will sever the member joining the two units together (see Fig. 6). With blade 19 in the second position of adjustment and the guide 37 in the position showing in Fig. 4, cutting edge 36 of blade 19 may be used to sever the side of the box in order to remove the top. (See Fig. 7.) When the guide 37 is fully retracted, as in Fig. 8, the sharp edge of blade 19 may be used to cut into a carton or for general cutting purpose. When the guide 37 is projected it acts as a safety guard to prevent the blade 19 from causing injury.

Although the present invention has been described in some detail by way of illustration 30 and example for purposes of clarity of understanding it is understood that certain changes and modifications may be practiced within the spirit of the invention and scope of the appended claims.

35 I claim:

1. A knife comprising a channel-shaped handle and a blade having a relatively thin anterior portion having a longitudinal edge, a notch cut into said longitudinal edge, said notch having a bottom edge substantially parallel to said longitudinal edge and spaced inwardly with respect thereto a first connecting edge slanted inwardly and forwardly from said longitudinal edge to said bottom edge and a second connecting edge, and a sharpened slitting edge on said blade located at the anterior end of said blade disposed at an acute angle with respect to said longitudinal edge, said blade being pivotally connected to said handle and arranged to be located in two positions, in one of said positions said notch portion of said blade extending beyond one end of said handle and in the other of said positions said notch portion being concealed within the channel of said handle and said slitting edge projecting beyond the opposite end of said handle.

2. A knife comprising a channel-shaped handle, a guide member attached to said handle, and a blade having a relatively thin anterior portion having a longitudinal edge, a notch cut into said longitudinal edge, said notch having a bottom edge substantially parallel to said longitudinal edge and spaced inwardly with respect thereto a first connecting edge slanted inwardly and forwardly from said longitudinal edge to said bottom edge and a second connecting edge, and a sharpened slitting edge on said blade located at the anterior end of said blade disposed at an acute angle with respect to said longitudinal edge, said blade being pivotally connected to said handle and arranged to be located in two positions, in one of said positions said notch portion of said blade extending beyond one end of said handle and in the other of said positions said notch portion being concealed within the channel of said handle and said slitting edge projecting

beyond the opposite end of said handle, said guide comprising a first arm, a second arm parallel thereto and a portion connecting said arms and disposed substantially normal thereto, said arms being substantially parallel to said blade, said first arm being connected to said handle, the under-surface of said second arm and a surface of said connecting portion constituting locating surfaces controlling the penetration and location of said blade with respect to a workpiece.

3. A knife comprising a channel shaped handle, a guide member attached to said handle, and a blade having a relatively thin anterior portion having a longitudinal edge, a notch cut into said longitudinal edge, said notch having a bottom edge substantially parallel to said longitudinal edge and spaced inwardly with respect thereto a first connecting edge slanted inwardly and forwardly from said longitudinal edge to said bottom edge and a second connecting edge, and a sharpened slitting edge on said blade located at the anterior end of said blade disposed at an acute angle with respect to said longitudinal edge, said blade being pivotally connected to said handle and arranged to be located in two positions, in one of said positions said notch portion of said blade extending beyond one end of said handle and in the other of said positions said notch portion being concealed within the channel of said handle and said slitting edge projecting beyond the opposite end of said handle, said guide comprising a first arm, a second arm parallel thereto and a portion connecting said arms being substantially normal to said blade, said first arm being slidably connected to said handle, the under-surface of said second arm and a surface of said connecting portion constituting locating surfaces controlling

the penetration and location of said blade with respect to a workpiece, said guide being moveable relative to said blade in an extended and retracted position, said slitting edges being shielded when said guide is in extended position.

5. A knife comprising a channel-shaped handle and a blade, said blade having a relatively thin anterior portion with a sharpened anterior, longitudinally disposed first edge and a hooked extremity portion projecting transversely outwardly from said first edge, the outwardly extending edge of said hooked extremity adjacent said first edge being sharpened, said blade also having a sharpened slitting edge located at the anterior end of said blade disposed at an acute angle with respect to said first edge, said blade being pivotally connected to said handle partially disposed within said channel and arranged to be located in two positions, in one of said positions, said hooked extremity of said blade extending beyond one end of said handle and in the other of said positions said notch portion being concealed within the channel of said handle and said slitting edge projecting beyond the opposite end of said handle.
